(57) **CLAIM**

The ornamental design for the plug and socket for temperature monitoring probe of patient monitor, as shown and described.

DESCRIPTION

FIG. 1 is a perspective view from one end of a plug and socket for temperature monitoring probe of patient monitor showing our new design;

FIG. 2 is a top view thereof;

FIG. 3 is a bottom view thereof;

FIG. 4 is a first side view thereof;

FIG. 5 is a second side view thereof;

FIG. 6 is a first end view thereof;

FIG. 7 is a second end view thereof;

FIG. 8 is a perspective view of the plug and socket for temperature monitoring probe of patient monitor showing a non-connected state with an associated socket;

FIG. 9 is a perspective view of the plug and socket for temperature monitoring probe of patient monitor shown in FIG. 8 showing a connected state with an associated socket.

FIG. 10 is a perspective view of the plug and socket for temperature monitoring probe of patient monitor showing a connected state with an associated socket installed in an interface panel of a patient monitor; and,

FIG. 11 is a perspective view of the plug and socket for temperature monitoring probe of patient monitor shown in FIG. 10 showing a non-connected state with an associated socket installed in an interface panel of a patient monitor.

The broken line showing is included for the purpose of illustrating portions of the article and forms no part of the claimed design.
